UNITED STATES PATENT OFFICE.

HENRY NOEL POTTER, OF NEW ROCHELLE, NEW YORK, ASSIGNOR TO
GEORGE WESTINGHOUSE, OF PITTSBURG, PENNSYLVANIA.

VACUUM ELECTRIC FURNACE.

No. 814,726.

Specification of Letters Patent.

Patented March 13, 1906.

Application filed July 23, 1903. Serial No. 166,667.

To all whom it may concern:

Be it known that **HENRY NOEL POTTER**, a citizen of the United States, and a resident of New Rochelle, in the county of Westchester and State of New York, have invented certain new and useful Improvements in Vacuum Electric Furnaces, of which the following is a specification.

The present invention is designed for highly heating refractory materials under reduced pressure, or for executing certain high temperature chemical reactions, where the speed of the reaction or its efficiency is improved by reduced pressure.

15 I have illustrated my furnace in the accompanying drawings, in which—

Figure 1 is a vertical section through the furnace. Fig. 2 is a reduced cross-section of a furnace embodying a simplified construction. Figs. 3, 4, and 5 illustrate details, and Fig. 6 is a diagram of the water connections of my furnace.

25 The main figure of the drawings illustrates a vertical furnace; but there is no reason other than that of convenience why the furnace should not occupy a horizontal or an angular position.

Referring first to Fig. 1, the numeral 1 represents a conducting-rod made of some highly 30 refractory material. The part here represented as a tube might be a rod of any preferred cross-section, usually round. In most cases this rod or tube will be of carbon or graphite, preferably the latter, owing to the 35 fact that it is easier to make good terminal connections with graphite than with other forms of carbon. The part 1, however, might be made of iridium, which would be of 40 advantage in certain classes of work, as when the furnace is used for roasting the glowers of Nernst lamps and the like. The tube shown 45 constitutes the core of the furnace, the material to be treated being arranged around the core. At the ends of the tube 1 are arranged 50 terminal blocks 2 and 3, of graphite or other appropriate conducting refractory material. These terminal blocks in turn make contact with metallic terminals 4 and 5, which are 55 preferably made of copper.

50 By referring to Fig. 4, it will be seen that the core 1, which in this figure is represented as a rod, is rounded to fit a rounded depression 40 in the terminal block 3.

In Fig. 3 a construction is illustrated which

is adapted to supply a good terminal connection between the core 1, when it is tubular in form, and the block 3. In this construction the lower end of the core is fitted with a solid rounded end block 12, which makes contact directly with the refractory terminal block 3. 55 A vent-hole 130 is shown as passing through the tube 1, and as an alternative arrangement, a vent-hole 140 (shown in Fig. 5) appears as passing through the end block 12. It will be understood that similar terminal connections 60 may be made between the rod or tube 1 and the upper refractory terminal block 2. The contact-surfaces in both instances are ground to a good fit, and by reason of the formation of cavities in the blocks 2 and 3 allowance can 65 be made for slight errors in alining the core 1 exactly parallel to the axis of the furnace. In case the block 3, for example, is shifted slightly to the right or to the left, no disturbance of the relative area of contact between 70 the parts 1 and 3 or the parts 1 and 2 will take place. The contacting parts are of calotte shape, as will be seen.

The contacts 4 and 5 are surrounded by water-jackets 6 and 7, the former being provided with inlet and outlet tubes 8 and 9, and the latter with similar tubes 10 and 11. To the under side of the block 5 is firmly attached, preferably by both soldering and by screws 12 12, a copper lead plate 13, a similar 85 plate 14 being attached by similar means to the top of the block 4.

A peculiarity of the upper terminal structure is that it has a thin-walled cylindrical metal tube 15, which extends beyond the water-jacket and is just large enough to slip over the body 16 of the furnace to be described-later on. Another peculiarity is that the entire terminal structure is supported upon several screws, two of which are shown 95 at 17 17. These screws pass through an upper extension 18 of the box inclosing the water-jacket 6 and support the weight of the upper terminal by resting upon brackets 19, which are firmly attached to the body of the 100 furnace by bolts or other means. Around the thin tube 15 and the upper part of the furnace-body 16 is drawn a rubber band 20, which prevents the ingress of air at this point, but permits the terminal 4 to be moved axially to correspond to varying lengths of the core 1.

The body of the furnace consists of the

double-walled tube 16, having an annular water-space 21 and provided with an inlet-tube 22 and an outlet-tube 23. The block 4 is provided with an opening, as shown at 24, and it is also fitted at the top with a screw-thread to receive the end of a tube 25, which passes through the plate 14 and into the block 4, as shown. The opening 24 is of the same bore as that of the tube 25 and forms a continuation of the tube down to the bottom of the block. At this point I make a groove or channel 26, opening into the space between the upper end of the main furnace-tube and the block 4 or the extended lower walls thereof. The tube 25 is for connection to the vacuum-pump, and it also has the function of allowing air to reenter the furnace upon the completion of the run. In case the core is made tubular the block 2 may also be perforated, as illustrated in Fig. 1, so as to connect the opening in the block 4 with the interior of the tube 1.

The bottom of the furnace-body rests upon a refractory insulating-ring 60, of asbestos or mica, which is of the same diameter as the adjacent parts, so that a rubber band 27 can be slipped over to make an air-tight joint at the lower end of the furnace.

The process of utilizing the furnace thus described is substantially as follows: The lower terminal is first placed upon a suitable support, the insulating-ring is put in place, the body of the furnace is set down upon the ring, and the band 27 is snapped into place. The terminal 3 is then inserted within the furnace from the top, and the material to be heated is placed around between the terminal 3 and the inner furnace-wall. Then the core 1 is held in place while more material to be heated is filled into the inner space of the furnace. By the accumulation of material thus caused the core is held firmly in place, and the material is firmly pressed down after the furnace is nearly filled. The terminal 2 is then put in place in the annular space between the said terminal, and the inner furnace-wall is filled with more material. Then the terminal 4 with its water-jacket is put in place, the screws 17 being retracted some to allow the full weight of the terminal to fall upon the block 2. After snapping the rubber band 20 into position the screws 17 are turned down until they just rest upon the brackets 19. The air between the particles of the material to be heated is now exhausted through the tube 25, the weight of the atmosphere upon the terminal 4 being carried by the screws 18, so that no greatly-increased pressure is brought upon the core 1. This explains a function of the screws 17, in the absence of which the atmospheric pressure would cause the core 1 to bend as soon as it becomes very hot. It will be seen that the described structure provides for a furnace having an articulated containing vessel hav-

ing seals for preventing the leakage of air or other gases.

The arrangement of water-circuits for effecting the cooling of the furnace-jacket consists of flexible tubing connected to a source of running water and joined to the tubes 8, 22, and 11. The source of water-supply is shown in Fig. 6, at 50, as being supplied with pipes 51 and 52, which are provided with cocks 53 and 54, respectively. From the cock 53 a pipe 55 leads to the inlet-tube 9, conducting to the water-jacket 6 of the cover. The exit takes place through the tube 8 and thence through a tube 56 to the inlet-pipe 22 of the body water-jacket 21. The water then passes out through the exit-pipe 23, which is so arranged as to draw water from the highest practicable point in the said jacket. It then passes through a connecting-pipe 57 to the sewer shown at 58. It will be observed that the cover referred to and the body are electrically of the same potential, and there is no reason why the water cannot pass through them in series. The case with the bottom water-jacket is different, inasmuch as this is at a different potential from the body of the furnace and therefore should not be connected therewith through a short length of hose, which would give rise to undesirable electrolytic effects. It is for this reason that the jacket 7 is supplied through a separate pipe 59, leading from the cock 54 to the inlet-tube 10, the water passing out through the exit 11, which is connected in its turn with the sewer 58 by a pipe 61. It might be thought that there is a water connection through the pipes 59 and 52, and the source of water-supply 50, the pipes 51 and 55 to the jacket of opposite potential. This is obviously true; but the length of the connection is so great and the conductivity of practically pure water so low as not to pass any appreciable current or give rise to any undesirable effects.

When the described steps have been carried out and the vacuum has been established, current is passed through the furnace by way of contact-plate 13, metallic terminal 5, terminal block 3, core 1, terminal block 2, metallic terminal 4, and the copper terminal 14.

In the furnace which I have constructed a drop of from eight to ten volts with a current of about four hundred amperes is used, the core being one-half inch in diameter and eight inches in length; but materially different diameters and lengths of the core and currents of different characteristics can be used with corresponding differences in the product and speed of operation. When cores of larger diameter are to be used, it is well to make them hollow, so as to increase their resistance and properly control the flow of current. When hollow cores are used, one or more vents must be provided to allow the in-

cluded air to be pumped out. This vent is preferably made close to one of the terminals. The vents may be dispensed with, however, and the pumping operation may be relied upon not only to exhaust the air from the interior of the core, but also to withdraw the major portion of the gases occluded in the graphite or carbon constituting the core. In Fig. 2 I show what seems to be the simplest possible construction for a furnace of this sort. The core is shown at 1, the refractory terminals at 2 and 3, the metallic terminals at 4 and 5, the latter constituting in this instance, together with the insulating-ring 60, of mica or other good insulating material, the chamber of the furnace, the pump connection shown at 30, the source of current at 31, the external connections at 13 and 14.

I claim as my invention—

- 20 1. An air-tight electric furnace having cool portions of an articulated containing vessel interposed between the highly-heated furnace interior and an exterior seal or seals.
  - 25 2. An inclosed electric furnace having an articulated container with at least one insulated joint separating portions of the container serving as furnace-electrodes.
  - 30 3. An electric furnace having metallic terminals so shaped that in conjunction with an insulating-partition, they constitute a containing vessel for said furnace.
  - 35 4. In an electric furnace, a refractory heating-conductor and terminals therefor, the shape of the abutting surfaces of said conductor and at least one of its terminals being conformably rounded.
  - 40 5. In an electrical apparatus, a pair of contacting electrical conductors having calotte-shaped contact-surfaces.
  - 45 6. In an electrical apparatus, a pair of cooperating graphite conductors having calotte-shaped contact-surfaces.
  - 50 7. In an electric furnace, a heating-conductor of carbon, carbon terminals contacting with opposite ends of said heating-conductor and metal terminals contacting with the end surfaces of said carbon terminals, and means for applying pressure to the said metal terminals, so that all the said parts are held in position thereby.
  - 55 8. An air-tight electric furnace for performing heating operations under reduced gas-pressure, having an articulated container with joints with seals adapted to be tightened by the excess of external pressure.
  - 60 9. In an electric furnace, a container of rounded or prismatic section, a smaller forming portion articulating therewith, and a seal clasping both articulating portions.
  - 65 10. A three-part container for an electric furnace, consisting of two large metal parts acting as electrical connections between the interior and the exterior portions of the furnace-circuit, together with a relatively small insulating part mechanically joining, but
- electrically separating the said large metal parts.
11. An electric furnace having a suitable chamber, means for articulating and sealing the said chamber, means for water-cooling the chamber, and means for creating a vacuum within the chamber. 70
  12. An electric furnace having a suitable chamber, a refractory conducting-core centrally disposed therein, conducting-terminals connected with the said core, and means for creating a vacuum in the space between the core and the chamber-walls. 75
  13. In an electric furnace, a suitable chamber, a core centrally disposed therein, terminal conducting-pieces for connecting the said core with an external circuit, and means for creating a vacuum in the space between the core and the chamber-walls. 80
  14. In an electric furnace, a suitable chamber, a core arranged within the same the ends of the said core being curved or rounded, in combination with terminal blocks having contact-surfaces conformably curved or rounded. 85
  15. In an electric furnace, a suitable chamber, a core of graphite or other refractory conducting material, the ends of the said core being curved or rounded, in combination with terminal blocks of similar refractory material engaging with the ends of the core and having contact-surfaces similarly curved or rounded, metal blocks engaging with the said terminal blocks, and provided with means for connection with an electric circuit. 90
  16. An electric furnace having a suitable chamber, a core centrally disposed therein, a conducting-support for the said core, a conducting terminal block adapted to press upon the end of the core, and means for relieving the pressure of the said terminal connection. 100
  17. An electric furnace having a suitable chamber, a core centrally disposed therein, a conducting-support for the said core, a conducting terminal block adapted to press upon the end of the core, means for relieving the pressure of the said terminal connection, and means for sealing the chamber. 105
  18. An electric furnace having a suitable chamber, a core centrally disposed therein, a conducting-support for the said core, a weighted conducting terminal block adapted to press upon the end of the core, means for relieving the pressure of the said terminal connection, means for sealing the chamber, and means for creating a vacuum in the chamber. 110
  19. In an electric furnace, a suitable chamber, a cap for the said furnace carrying conducting-terminals and provided with a depending sleeve adapted to slip over and surround the said chamber, in combination with a sealing-band surrounding the joint between the said chamber and the said sleeve. 115
  20. In an electric furnace, a suitable chamber, a cap for the said furnace carrying conducting-terminals and provided with a depending sleeve adapted to slip over and surround the said chamber, in combination with a sealing-band surrounding the joint between the said chamber and the said sleeve. 120
  21. In an electric furnace, a suitable chamber, a cap for the said furnace carrying conducting-terminals and provided with a depending sleeve adapted to slip over and surround the said chamber, in combination with a sealing-band surrounding the joint between the said chamber and the said sleeve. 125
  22. In an electric furnace, a suitable chamber, a cap for the said furnace carrying conducting-terminals and provided with a depending sleeve adapted to slip over and surround the said chamber, in combination with a sealing-band surrounding the joint between the said chamber and the said sleeve. 130

20. In an electric furnace, a suitable chamber having double walls for providing a water-cooling space, inlet and outlet tubes leading to and from the water-space, and a tube connecting with the chamber, the said last-named tube being adapted to be connected with a suitable vacuum-pump. 35
21. In an electric furnace, a suitable chamber, an independent insulated support for the walls thereof, a cap covering the top of the said chamber, and means for sealing the joints between the chamber and its support at one end and the chamber and its cap at the other end. 40
22. In an electric furnace, a suitable chamber, an independent insulated support for the walls of the said chamber, a central metallic terminal, and a refractory conducting block within the chamber, covering the said metallic terminal and making contact therewith. 45
23. In an electric furnace, a suitable chamber, an insulated support for the walls thereof, a central metallic terminal in the said support, a core of refractory conducting material within the chamber, terminal blocks of refractory conducting material for the said core, a cap for the said chamber carrying a metallic terminal in contact with one of the said blocks, the said metallic terminal being 50
- centrally located with respect to the said cap, water-jackets for the said metallic terminals and for the furnace-chamber, and means for connecting the terminal, with an electric circuit. 55
24. In an electric furnace, a suitable chamber, a hollow core within the same, means for creating a vacuum within the chamber, and a vent connecting the interior of the core with the chamber. 60
25. In an electric furnace, an air-tight chamber, consisting in part of an impervious packing clamped between thin metal portions of said chamber, the said metal portions being water-cooled wherever they adjoin the said packing. 65
26. In an electric furnace, a containing-chamber of two or more parts separated by insulating or packing material, said constituent parts of said chamber being water-cooled where they adjoin said insulating or packing material. 70

Signed at New York, in the county of New York, and State of New York this 15th day of July A. D. 1903.

HENRY NOEL POTTER.
